UNITED STATES PATENT OFFICE

LAZENBY C. HAMLINK, OF CLEVELAND HEIGHTS, OHIO, ASSIGNOR TO THE GAS MACHINERY COMPANY, OF CLEVELAND, OHIO, A CORPORATION OF OHIO

COKING GAS OVEN

Application filed April 28, 1927. Serial No. 187,243.

My invention relates to coking gas-ovens and particularly to that class of apparatus in which a plurality of parallel retorts is employed, each of the sides of which is associated with a heating unit for supplying the required heat to the coal in the retorts for making the desired gas product and by-product coke which heating units each includes regenerators for conserving the heat of the gases of combustion; together with valve mechanisms for controlling the flow of the fuel-gas, the flow of the air for supporting the combustion of the latter and the flow of the gases of combustion, whereby the direction of flow of the latter through the units may be reversed and the heat of the regenerators applied to such air. Also in this type of apparatus, two waste-gas and two fuel-gas flues are employed, which, by means of the valve mechanism, are alternately rendered operative, the fuel-gas flues or conduits being connected with a source of fuel-gas supply. That is, the valve mechanism may be so manipulated that fuel-gas first passes through one fuel-gas flue or conduit, then with air passes through the heating unit in one direction and is burned in such unit. The gases of combustion then pass out through the one waste-gas flue. Or the valve mechanism may be so manipulated as to cause the fuel-gas to first pass through the other fuel-gas flue or conduit, then with air through the heating unit in the opposite direction and burned in said unit, the gases of combustion then passing out through the other waste-gas flue.

Apparatus of this type is generally referred to as a "by-product gas-oven" since commercially usable gas is the product of main value and coke is a by-product.

Heretofore in apparatus of this type communication between the fuel-gas flues and each heating unit has been controlled by two separate valves. There were, in consequence, twice as many of these valves as there were heating units and the element of expense was such that these valves had to be constructed from materials and in a manner such that they were not capable of withstanding a temperature of over approximately 700° F. without injury.

Inasmuch as the object of such coking gas-ovens is to make as large a quantity of gas as possible and to dispose of same commercially, a separate and cheaper source of fuel-gas has been provided for the heating units 55 and the most economical gas for this purpose is producer-gas.

A suitable gas-producer has been therefore employed to furnish this fuel-gas and was suitably connected with the apparatus. It 60 has, however, been impractical to connect the gas-producer directly with the fuel-gas ducts without first cooling the gas, inasmuch as the producer-gas would enter the apparatus at a temperature of about 1200° F., or over, and 65 would eventually impair or destroy the controlling valves above referred to. Such cooling action, however, resulted in a loss of thermal efficiency, as will be understood by those skilled in the art, and required the presence 70 in the apparatus of a regenerator for reheating this gas in order to produce the proper flame temperature in the combustion chambers.

The general object of the present invention 75 is to increase the efficiency of coking gas-ovens of the above-described type, one of the specific objects being to provide a structure in which the producer-gas source may be connected directly with the apparatus, that is, 80 without subjecting the fuel-gas to a cooling operation before it passes into the heating units, and thereby enabling me to take advantage to the fullest extent possible of the economic value of the sensible heat in such producer-gas.

The said invention consists in characteristics of structure and combinations of parts hereinafter fully described and particularly 90 pointed out in the claims.

In the annexed drawings:

Figure 1 represents a plan of a coking gas-oven of the above-described type and embodying my invention.

Fig. 2 represents a front elevation.

Fig. 3 represents a vertical longitudinal broken section on an enlarged scale, taken upon the planes indicated by line III—III, Fig. 1, and viewed in the direction indicated 100 by the arrows.

Fig. 4 represents a transverse section, on said enlarged scale, taken upon the planes indicated by line IV—IV, Fig. 3, and viewed in the direction indicated by the arrows.

5 Fig. 5 represents a partial transverse section, on said enlarged scale, taken upon the plane indicated by line V—V, Fig. 3, and viewed in the direction indicated by the arrows.

10 Fig. 6 represents a partial transverse section on said enlarged scale, taken upon the planes indicated by line VI—VI, Fig. 3.

15 Fig. 7 represents a partial horizontal section taken upon the plane indicated by line VII—VII, Fig. 4, and viewed in the direction indicated by the arrows.

20 Fig. 8 represents a partial horizontal section taken upon the plane indicated by line VIII—VIII, Fig. 4.

25 Fig. 9 represents a horizontal section taken upon the plane indicated by line IX—IX, Fig. 4.

30 Fig. 10 represents a horizontal section of the valve mechanism taken upon the plane indicated by line X—X, Fig. 2, viewed in the direction indicated by the arrows.

35 Fig. 11 represents a transverse vertical section of said valve mechanism, taken upon the plane indicated by line XI—XI, Fig. 1.

40 Fig. 12 represents a transverse vertical section taken upon the plane indicated by line XII—XII, Fig. 1, and

45 Fig. 13 represents a longitudinal vertical section taken upon the plane indicated by line XIII—XIII, Fig. 1.

In the illustrated embodiment of my invention, suitable materials such as brick, masonry and steel are employed to form a main battery structure 1, embodying a plurality of parallel and vertical oven chambers 2 extending transversely of the structure 1, as shown in Fig. 3, each provided at the top with suitable charging openings 3 and covers 4 therefor, and an oven-gas outlet 5, Fig. 5, all of these outlets being connected to a main take-off duct 6, for conducting the oven-gas to a suitable gas-holder (not shown) as will be understood.

50 In this main structure is also provided a plurality of heating units for heating the two opposite sides of the oven chambers. Each of these units includes a combustion chamber 7 and these chambers alternate longitudinally of the battery, with the oven chambers 2, so that each side of each oven chamber is laterally adjacent to a combustion chamber 7 as shown in Fig. 3.

55 Each combustion chamber is sub-divided into a plurality of vertical front heating combustion flues 8, and rear heating flues 8' by vertical walls 8² terminating short of the top of the oven chamber to form a horizontal passage 9, Figs. 3 and 4.

60 Beneath the front part of each combustion chamber and parallel therewith are two pas-

70 sages 10 and 11, and beneath the rear part thereof and parallel with such chamber are two similar passages 10' and 11', the inner ends of these two pairs of passages being separated from each other by a wall 12, and the outer ends being normally closed to the exterior by doors 13 and 14, as shown in Figs. 4, 6 and 8.

75 The bottom of each vertical heating flue 8 and 8' is provided with an opening 15 or 15' which communicates with two laterally diverging passages or ports, 16 and 17 or 16' and 17', whose lower ends respectively communicate with the passages 10 and 11, and 10' and 11', Figs. 3, 4, and 6. The latter passages are each formed at their sides with ledges 18 and 18', respectively, upon which rest loosely placed damper-bricks 19 and 19', Fig. 8, which may be used to vary the extent of communication of the passages 16 and 17 and 16' and 17' with the passages 10, 11, 10' and 11' by sliding them along the ledges 18 and 18' to partially cover the bottoms of said passages 16 and 17 and 16' and 17'.

80 Beneath each combustion chamber 7 are two transversely aligned vertical regenerators 20 and 20' whose inner ends are separated by a longitudinal wall 21, Figs. 3 and 6, and adjacent thereto and parallel with these regenerators are two narrow vertical fuel-gas passages 22 and 22' respectively, and also aligned transversely of the main battery structure, Figs. 3, 4 and 9.

85 These fuel-gas passages 22 and 22' are provided internally with stay-bricks 23 for supporting their walls, as shown in Figs. 3 and 4, and their inner ends are separated from each other by the wall 21.

90 The upper end of each front regenerator 20 is connected with a passage 11 by means of a plurality of vertical passages 24, corresponding in number with the heating flues 8 which are located above the regenerators 20, Fig. 6; and each of the front fuel-gas passages 22 is connected with a passage 10, by the same number of vertical passages 25, Fig. 4. Similarly the upper end of each rear regenerator 20' is connected with a passage 11' by means of a plurality of vertical passages 24', corresponding in number with the heating flues 8' which are located above the regenerators 20', and each of the rear fuel-gas passages 22' is connected with a passage 10' by the same number of vertical passages 25'.

95 The bottom of each of the front regenerators 20 is connected with a common longitudinally extending horizontal waste-gas flue 26 by means of a vertical passage 27, and the bottom of each of the rear regenerators 20' with a common longitudinally extending horizontal waste-gas flue 28 by means of a vertical passage 29, as shown in Figs. 3 and 6. The degree of communication between the regenerators and the waste-gas flues 26 and 100

28 may be controlled by slidable damper-bricks 30, Figs. 6 and 9.

The bottom of each of the front fuel-gas passages 22 is connected with a common longitudinally extending horizontal fuel-gas flue 31 by means of a vertical passage 32, and the bottom of each rear fuel-gas passage 22' is connected with a common longitudinally extending horizontal fuel-gas flue 33 by means of a vertical passage 34, as shown in Fig. 4. The degree of communication between the fuel-gas passages 22 and 22' and the fuel-gas flues 31 and 33 may be controlled by slidable damper-bricks 35, Figs. 4 and 9.

15 Below each regenerator 20 and 20' is a horizontal air-supply passage 36 or 36' whose communication with the atmosphere is controlled by a damper 37 or 37', Fig. 6. As has been common practice heretofore, suitable 20 means are provided for simultaneously actuating all of the front dampers 37, and similar means for simultaneously actuating all of the rear dampers 37', and which it will hence not be necessary to further describe.

Access to the damper-bricks 30 controlling communication between the regenerators 20 and 20' and the waste-gas flues 26 and 28 is afforded through the outer ends 30 of the air-passages 36 and 36' and to the damper-bricks 35 controlling communication between the fuel-gas passages 22 and 22' and the fuel-gas flues 31 and 33 through the outer openings 38 and 38' normally closed by doors 35. 39.

Each heating unit therefore consists of two transversely alined vertical regenerators, two transversely alined vertical fuel-gas passages respectively adjacent the regenerators, 40 a combustion chamber above and communicating with both of the regenerators and fuel-gas passages, the communication between the regenerators and combustion chambers being controllable and the communication 45 between the fuel-gas passages and combustion chambers being likewise controllable. These heating units also include the air-supply passages 36 and 36' for the regenerators 20 and 20', respectively.

50 It will be noted from the description and drawings that the direct communication between the fuel-gas flues 31 and 33 and the heating units is permanently open as is also the communication between the said units and the waste-gas flues 26 and 28, the amount of 55 opening being controllable by the damper-bricks 35 and 30, respectively as described above.

Each of the fuel-gas flues 31 and 33 is 60 closed at one end of the main battery structure as shown in Fig. 1 at 31a and 33a, and extends beyond the other end of said structure, the left-hand end thereof as illustrated, and access to these latter extending ends is 65 controlled by a reversing valve 40 of any

suitable construction designed to be used successfully under high temperature conditions. A suitable valve for such purpose is a water-sealed reversing valve such as is shown and described in United States Patent No. 1,045,749, which per se forms no part of my present invention and I have illustrated such a valve as applied to my improved apparatus, in the drawings, Fig. 1, 2, 10, 11, 12 and 13.

The left-hand extending ends of the said two fuel-gas flues terminate under the casing 41 of the valve 40, Figs. 1 and 12, and communicate with the interior of said casing through vertical passages 31' and 33' respectively, and the top of such casing is connected with a downcomer pipe 42 which in turn is connected with a gas-producer 44 which supplies hot fuel-gas. A dust-catcher 43 may be interposed between the gas-producer and downcomer pipe.

Between the end portions of the two fuel-gas flues 31 and 33 is an auxiliary waste-gas flue 45 which communicates with the interior of the casing of the valve 40 by means of a vertical passage 45' and this communication is controlled by a slide-valve 46, Figs. 12 and 13.

The other end of this flue 45 communicates with the stack 47, Fig. 1.

The valve 40 is provided with the movable member 48, Figure 12, which may be shifted to permit communication between the downcomer 42 and either the fuel-gas flue 31 or the fuel-gas flue 33. In so doing communication is established between the auxiliary flue 45 and that fuel-gas flue which is shut off from communication with the downcomer 42.

Each of the waste-gas flues 26 and 28 is closed at one end of the main battery structure as shown at 26a and 28a, Fig. 1, and extends beyond the other end of said structure, the left-hand end thereof as illustrated.

The extending ends of the two waste-gas flues 26 and 28 terminate under the casing 50, Figure 11, of a valve 49 similar to valve 40, and communicate with the interior of said casing through vertical passages 26' and 28' respectively. The auxiliary waste-gas flue 45 extends between the end portions of the two waste-gas flues, Figs. 1 and 11, and communicates with the interior of the casing 50 of reversing valve 49 by means of the vertical passage 45a.

The movable valve-member 51 of the valve 49, may be shifted so as to establish communication between the auxiliary waste-gas passage 45 and either one of the waste-gas flues 26 and 28 to the exclusion of the other, as will be understood.

Description of operation

Let it be assumed that the two valves 40 and 49 are set so that their movable members 48 and 51 are in the positions shown in full

70

75

80

85

90

95

100

105

110

115

125

130

lines in Figs. 11 and 12, respectively. Under such conditions the rear air-control dampers 37' are given their open position and the front air-control dampers 37, given their closed position, as shown in Fig. 6.

Let it also be assumed that the apparatus has been in previous operation in a manner such as to have heated up the rear regenerators 20'.

The hot producer-gas will therefore pass from the producer 44 over to and down the downcomer pipe to the interior of the casting 41 of valve 40. Thence it passes into the rear fuel-gas flue 33 and up through the passages 34 and into and through the rear fuel-gas passages 22'. From the latter it passes up through the passages 25' to the transverse passages 10', thence to the passages 16' and into the rear heating flues 8' which are above the rear regenerators 20' and fuel-gas passages 22'.

Simultaneously with the above-described direction of travel of the fuel-gas, air passes into the rear air-passages 36' up through the heated rear regenerators 20', out through the passages 24' and into the transverse passages 11'. From the latter the heated air passes up through the passages 17' into the rear heating flues 8' into which the fuel-gas is passing. The air and gas therefore become mixed in these heating flues 8' and combustion of the gas is effected therein.

The gases of heating pass out of the rear combustion flues into the passages 9 and over to the heating flues which are above the front regenerators 20.

As will be noted from Fig. 11, the front waste-gas flue 26 is connected with the auxiliary waste-gas flue 45 and hence with the stack. It will also be noted from Fig. 12 that the front fuel-gas flue 31 is connected with the said auxiliary flue 45, but this connection is limited by the slide-valve 46, the latter being set so as to materially restrict the draft from the fuel-gas flue 31 to the stack.

The greater portion of the gases of combustion, therefore, pass from the front combustion chambers down through the passages 17 connected therewith, through passages 24 and into and through the front regenerators 20, heating the latter. From the regenerators 20, they then pass through the passages 27 connected therewith, into the front waste-gas flues 26, into valve-member 51, over into the waste-gas flue 45 to the stack.

A much smaller quantity of these gases and which is regulatable by the slide-valve 46, passes from the front heating flues 8, down through the passages 16 connected therewith, through passages 25, into and through the front fuel-gas passages 22, through the passages 32, into and through the front fuel-gas flue 31, into valve-chamber 48, and past the valve 46, through passage 45' (Fig. 13) to auxiliary waste-gas flue 45

and thence to the stack, thus purging the front fuel-gas passages 22 and the front fuel-gas flue 31 of any air which might have gained access thereto by leakage or otherwise, and so preventing the formation of an explosive mixture when the operation is reversed as hereinafter described.

To reverse the above-described operation, the valves 40 and 49 are operated to shift their movable members over to their other positions, rear air dampers 37' are closed and front air dampers 37 are opened. Valve 40 will then establish connection between the downcomer 42 and the front fuel-gas flue 31 and also establish connection between the flue 45 (and hence the stack) and the rear fuel-gas flue 33. Valve 49 will then establish connection between the flue 45 (and hence the stack) and the rear waste-gas flue 28.

Fuel-gas from the producer will in consequence flow into the front fuel-gas flue 31, up through the front fuel-gas passages 22 and into the front heating flues 8.

Air will flow into the front air-supply passages 36 up through the heated front regenerators 20 and into the front heating flues 8 where it supports the combustion of the fuel-gas. The gases of combustion pass up to and through passages 9 and down the rear heating flues 8'. The greater part of these gases then passes through passages 17', then passes through and heats the rear regenerators 20', then passes into and through the rear waste gas flue 28, through valve 49 to the stack. A smaller amount of the gases passes through passages 16' and purges the rear fuel gas passages 22' and the rear fuel gas flue 33, as a result of the connection of the rear fuel-gas flue with the stack by the valve 40, as will be understood.

It will be noted from the above construction, that by providing valve mechanism for controlling the influx of fuel-gas into the fuel-gas flues 31 and 33, and for controlling the efflux of the gases of combustion from the waste-gas flues 26 and 28, all of the direct connections between the fuel-gas flues and heating units, and between the heating units and the waste-gas flues may be left permanently open, after being set as desired by means of the damper-bricks 35 and 30, respectively, thus eliminating the necessity of providing separate valves for controlling access to and discharge from said units. A valve-mechanism for complete control and capable of effecting the necessary reversal, is therefore provided, which is greatly simplified as compared with the previous practice, and which may therefore be made heat-resisting to any required degree without prohibitive expense.

The hot or raw producer-gas may hence be introduced directly into the apparatus without cooling, by washing, scrubbing or other-

wise, and enter the fuel-gas passages and combustion chambers at a high degree of temperature, usually about 1300° F.

It will also be seen from the above-described construction that the damper-bricks 19 and 19' by being placed intermediately of the bottom of the combustion chambers and tops of the fuel gas passages 22, 22' and the regenerators 20 and 20' are out of the direct influence of the destructive action of the high heat generated in the combustion chambers during combustion, thus tending to prolong the life of these bricks and are also in a position in which they are readily accessible for adjustment.

By eliminating the multiplicity of controlling valves heretofore employed and as heretofore described, both the fuel-gas flues and waste-gas flues may be placed beneath the apparatus, and incorporated in the masonry fundation structure as shown.

It will be further noted that inasmuch as the fuel-gas need not be reheated, a regenerator for heating such gas is not required. This make it possible to make the fuel-gas passages 22 and 22' narrow and the regenerators 20 and 20' wide, as shown in Figure 3, thus providing a greater regenerator surface for the air than has heretofore been possible in by-product gas ovens using producer-gas as fuel. At the same time, the total regenerator surface is reduced as compared to that heretofore required, thus resulting in economy of construction.

What I claim is:

1. In a coke oven battery, a series of alternate coking chambers and combustion chambers for heating the same arranged side by side in a row, a regenerator unit below each of said combustion chambers, each of the regenerator units comprising two regenerators and each of the regenerators of each of said units communicating with the combustion chamber above the unit, two fuel-gas flues extending along said battery and communicating with each of said combustion chambers and an air inlet for each of said regenerators and means for controlling same; a single reversing valve for controlling all of the fuel-gas flow into both of said fuel-gas flues; two waste-gas flues extending along said battery, the one communicating with one of the regenerators of each of said units and the other waste-gas flue with the other regenerator of the same unit; and means for controlling the out-flow from said waste-gas flues.

2. A coke oven battery comprising a series of alternate coking chambers and combustion chambers for heating the coking chambers arranged side by side in a row; a regenerator unit associated with each combustion chamber, each regenerator unit including two regenerators each of which has communication with its associated combustion

chamber and each regenerator having an air inlet; means for controlling the air inlets; two fuel conduits extending along the battery and having communication with all the combustion chambers; two waste-gas flues extending along said battery and communicating with the regenerator units; an outlet flue for waste gases adapted to communicate with said waste-gas flues; a single reversing valve associated with the fuel conduits and adapted to control the flow of fuel from a source of supply alternately through said conduits to all the combustion chambers; and valve mechanism associated with the waste-gas flues and adapted to control the flow of waste-gas from said two waste-gas flues to the outlet flue.

3. A coke oven battery comprising a series of alternate coking chambers and combustion chambers for heating the same arranged side by side in a row; a regenerator unit associated with each combustion chamber and including a front regenerator communicating with the front portion of its associated combustion chamber and a rear regenerator communicating with the rear portion of the same combustion chamber; an air inlet for each of said regenerators; means for controlling the air inlets; a waste-gas flue system including two waste-gas flues extending along the battery, one of said flues communicating with the front regenerators and the second flue communicating with the rear regenerators, an outlet-flue adapted to communicate with said waste-gas flue, and a single reversing valve associated with said flues and adapted to place said waste-gas flues alternately in communication with the out-let flue; and a fuel-gas conduit system including two conduits extending along the battery, one conduit having communication with the front portions of the combustion chambers and the second conduit having communication with the rear portions of the combustion chambers, and means associated with said conduits and adapted to control the flow of fuel gas through the conduits to the combustion chambers.

4. A coke oven battery comprising a series of alternate coking chambers and combustion chambers for heating the same arranged side by side in a row; a regenerator unit below each of said combustion chambers, each of the regenerator units comprising two regenerators each of which communicates with the combustion chamber above the unit; an air inlet for each of said regenerators; means for controlling the air inlets; two fuel-gas conduits extending along said battery and communicating with each of said combustion chambers; a single reversing valve for controlling the fuel-gas flow alternately into said fuel-gas conduits; two waste-gas flues extending along said battery and communicating with the two regenerators of each of

the regenerator units respectively; an outlet flue for the waste gases adapted to communicate with said waste-gas flues; and a single valve for controlling the outflow of waste gases from said waste-gas flues to said outlet flue.

5. In a coke oven battery having a series of coking chambers and heating units, the heating units including combustion chambers, a front series and a rear series of regenerators communicating with spaced portions of the combustion chambers and having valved air inlets, and the coking and combustion chambers being disposed side by side in a row and in alternate relation to each other; a gas flue system comprising two waste-gas flues extending along the battery, one flue communicating with the front series of regenerators and the second flue communicating with the rear series of regenerators, an outlet-flue adapted to communicate with said waste-gas flues, a reversing valve adapted to place said two waste-gas flues in communication with said outlet-flue, two fuel-gas conduits extending along the battery, one of said conduits having communication with one portion of each combustion chamber and the second conduit having communication with another portion of each combustion chamber, a valve associated with said conduits, and a passage extending from the last-mentioned valve to the outlet-flue, said last-mentioned valve being adapted to connect one of the fuel-gas conduits with a source of fuel-gas and to connect the other conduit with said passage.

6. A coke oven battery comprising a series of alternate coking chambers and combustion chambers for heating the same arranged side by side in a row; a regenerator unit below each combustion chamber, said unit including a front regenerator communicating with the front portion of the combustion chamber directly above and a rear regenerator communicating with the rear portion of the same combustion chamber; valved air inlets for said regenerators; a waste-gas flue system including two waste-gas flues extending along the battery, one flue communicating with all the front regenerators and the second flue communicating with all the rear regenerators, an outlet-flue adapted to communicate with said waste-gas flues, and a reversing valve interposed between the two waste-gas flues and the outlet-flue and adapted to place either of said two waste-gas flues in communication with the outlet-flue; and a fuel-gas conduit system including two fuel-gas conduits extending along the battery, one conduit having communication with the front portion of each combustion chamber and the second conduit having communication with the rear portion of each combustion chamber, and a valve mechanism associated with said conduits and communicating

with the outlet-flue, said valve mechanism being adapted to connect one of said two conduits with a source of fuel-gas and the other conduit with the outlet-flue.

7. In a coke oven battery, a series of coking units each comprising a coking chamber and a combustion chamber side by side for heating the same, said units being positioned in a row so that the coking chambers alternate with the combustion chambers; a series of auxiliary units below the coking units, each auxiliary unit corresponding to a coking unit and including two regenerators and a fuel passage adjacent thereto, each regenerator being substantially wider than the fuel passage adjacent thereto, and the width of each auxiliary unit being substantially the same as the width of the corresponding coking unit; conduits connecting each combustion chamber to the two regenerators and the fuel passage of the corresponding auxiliary unit; two fuel conduits extending along the battery, some of the fuel passages communicating with one of said fuel conduits and the balance of the fuel passages communicating with the other fuel conduit; and a single reversing valve for controlling the flow of fuel through said fuel conduits to all of the fuel passages.

8. A coke oven battery comprising a series of coking units positioned side by side in a row, each coking unit consisting of a coking chamber and a combustion chamber contacting therewith and the units being positioned so that the coking chambers alternate with the combustion chambers; a series of auxiliary units positioned side by side in a row below the front portions of the coking units, each auxiliary unit being operatively associated with one of the combustion chambers and including a regenerator and a fuel-gas passage adjacent thereto, each regenerator being substantially wider than the fuel-gas passage adjacent thereto and the combined width of one regenerator and its adjacent fuel-gas passage being substantially the same as the combined width of the corresponding coking and combustion chambers associated therewith; a second series of similar auxiliary units similarly positioned below the rear portions of the coking units; air inlets for the regenerators; means for controlling the inflow of air through said inlets; a waste-gas flue system including two waste-gas flues extending along the auxiliary units, one flue communicating with the regenerators of one series of auxiliary units and the second flue communicating with the regenerators of the other series of auxiliary units, an outlet-flue adapted to communicate with said waste-gas flues, and a reversing valve adapted to place the two waste-gas flues alternately in communication with the outlet-flue; and a fuel-gas feeding system including two fuel-

gas conduits extending along the auxiliary units, one conduit communicating with the fuel-gas passages of one series of auxiliary units and the second conduit communicating with the fuel-gas passages of the other series of auxiliary units, and a reversing valve adapted to place said two fuel-gas conduits alternatively in communication with a source of fuel-gas.

10 Signed by me this 21st day of April, 1927.
LAZENBY C. HAMLINK.
